INVENTOR.

BY

A. G. Burns ATTORNEY.

UNITED STATES PATENT OFFICE

ALFRED EVARD, OF FORT WAYNE, INDIANA

BURIAL VAULT

Application filed February 16, 1931. Serial No. 516,058.

This invention relates to improvements in burial vaults and the object thereof is to provide an enclosure for a casket for installation in the grave whereby water through seepage or such as forms by condensation is prevented from saturating the casket.

An illustrative embodiment of the invention is shown in the accompanying drawings, in which:—

Fig. 1 is a side elevation of an enclosure containing a casket and in which the invention is embodied, portions thereof being broken away; and

Fig. 2 is an end elevation of the same with a portion thereof broken away.

The illustrative embodiment consists of a base plate 1 constructed of cement, the edges of the plate being formed so as to present a series of offsets 2, 3 and 4 that extend entirely around the base and are disposed in successive order in vertical planes spaced apart from the innermost offset 2 to the outermost offset 4. Thus there is provided a pair of seats 5 and 6 disposed in horizontal planes spaced apart upon which the lower edge of an inner cover 7 for the casket rests, the lower edge of the cover having a rabbet formed therein to fit the offset; and also a pair of seats 8 and 9 disposed in horizontal planes spaced apart upon which rests the lower edge of an outer cover 10, said lower edge having a rabbet formed therein to fit the offset 4.

The base 1 has made therein a series of transversely disposed ducts 11, the ends of which extend entirely through the corresponding offsets 2, 3 and 4 and across the seats 6 and 8, the seats 5 and 9 being uninterrupted by said ducts. Thus, the contact of the inner portion of the lower edge of the inner cover 7 upon the seat 5 extends unbroken entirely around the base, while the contact of the outer portion of the lower edge of said cover 7 rests upon portions 12 of the seat 6 that are spaced apart because of the ducts 11 that intervene therebetween; and the contact of the inner portion of the lower edge of the outer cover 10 upon the seat 8 is upon portions 13 that are spaced apart because of the ducts 11, while the contact of the

outer portion of the lower edge of said cover 10 upon the seat 9 extends unbroken entirely around the base.

The covers 7 and 10 are each formed of cement in a single piece without joints so that they are entirely closed except at their bottoms so that escape of air through their walls is prevented. When the covers are in place with their lower edges seated upon the base any condensations of moisture that may accumulate within the covers and creep along the contacting portions of the base and covers will seep outwardly leaving the casket 14 dry. The ducts 11 afford spaces for the reception of seepage from within the covers, and the ducts become drained by seepage of the water therefrom past the offset 4 and between the outer edge portion of the outer cover and the seat 9.

Should the grave filling of earth surrounding the vault become saturated, entrance of water therefrom into the vault is prevented because of the content of air within the covers which is confined therein. As portions of the seats 6 and 8 on the base are interrupted by the ducts seepage of water into the vault between the lower edges of the covers and the base by capillary attraction is thereby averted. The water upon seeping inwardly between the spaced portions 13 and 12 of the seats 8 and 6 and the corresponding contacting edges of the covers thereon drains back into the ducts 11, from whence it is absorbed by the earth subsequently as the earth dries.

In the ordinary structure where the edge of the cover rests upon the earth or upon a base and the contact of the cover with the earth or the base is continuous and unbroken, moisture absorbed from the surrounding saturated earth is drawn by capillary attraction into the cavity within the cover. However, in the present structure the seats 6 and 8 are broken at points where the ends of the ducts open through the sides of the base and where the tendency of attraction of moisture does not occur but leaves spaces for the drainage of moisture from those contacting surfaces between the covers and the base that

tends to accumulate through capillary attraction.

The ends of both covers 7 and 10 have formed upon each end thereof an outwardly extending ledge 15 which provide means for the attachment of a grapple or any suitable device whereby the covers may be conveniently handled during transportation and lowering them into position within the grave. As the grapple or other similar expedient may be of any suitable construction and immaterial to the present invention, such grapple or expedient is not herein disclosed.

In making an installation of the vault, the base 1 is first positioned upon the bottom of the grave, after which the casket 14 is lowered and centered upon the base. The cover 7 is then suspended from a grapple and lowered into position upon the base over the casket 20 with its lower edges resting upon the seats 5 and 6 so that the casket is completely enclosed by the base and the cover 7. The outer cover 10 is then likewise placed into position over the inner cover 7 with its lower edges resting upon the seats 8 and 9 so that the inner cover is completely encased thereby. The outer ends of the ducts 11 in the base extend outwardly beneath the corresponding edges of the inner cover 7 and have communication with the space 16 between said covers, and extend also beneath the inner portion of the lower edge of the outer cover, so that said ducts receive the water which forms by condensation upon the inner walls of the outer cover and the outer wall of the inner cover, or that is drawn by capillary attraction into the vault through the joint between the outer cover and the base.

I claim:

1. In a burial vault, a base having a series of offsets extending entirely around its edges and disposed in vertical planes spaced apart and corresponding horizontal seats, and having also a series of ducts the ends of which extend through said offsets and across the intermediate seats whereby seat portions on the base between said offsets are spaced apart, an inner cover closed about its top, sides and ends, and having a rabbet formed in its lower edge to fit the innermost offset on said base, and an outer cover spaced from said inner cover and closed about its top, sides and ends, adapted to enclose said inner cover and having a rabbet formed in its lower edge to fit the outermost offset on said base, said covers each having formed on the ends thereof an outwardly extending ledge, said ducts having communication with the space between said covers.

2. In a burial vault, a base having a series of seats disposed around its edges, and having also a series of ducts extending transversely therethrough, the ends of which ducts extend across the intermediate seats whereby certain seat portions on the base are inter-

sected thereby, and inner and outer covers each of which is closed at its top, sides and ends, the lower edges of which covers are adapted to rest upon the corresponding seats, there being a space intervening between said covers that has communication with said ducts.

3. In a burial vault, a base adapted for the support of a casket and having a series of ducts disposed between the top and bottom 75 of the base, and inner and outer covers, the top, side and end walls of each cover being integral, said covers being adapted to rest upon the base in spaced relation with each other, said ducts having communication at 80 each end with the space between said covers.

4. A burial vault consisting of a base, an inner cover, and an outer cover, said covers being telescopically positioned upon said base, there being a space between said covers, 85 said base having ducts therein communicating with the space between said covers.

In testimony whereof I affix my signature.

ALFRED EVARD.
